[57] ABSTRACT

A postcard coin carrier and method wherein a unitary paperboard card of generally rectangular configuration having a transverse line of potential folding to provide an end flap, the end flap being equipped with a U-shaped pattern of remoistenable adhesive so as to provide a pocket for enclosing a coin or bill, the card being equipped with an integral extension separated by a line of perforation -- the extension carrying advertising matter and providing an edge portion for securing to a larger sheet, such as a publication; the edge portion of the extension also being equipped with pin-receiving openings for high speed application of the extension-equipped card to the publication.

FIG. 5

POSTCARD COIN CARRIER, AND METHOD

BACKGROUND AND SUMMARY OF THE INVENTION

Although postcard coin carriers have been known in the past—see, for example, U.S. Pat. No. 2,227,179—, these have suffered from a number of defects extending not only to the usage in actual transmission of coins, but in prior handling operations such as the dissemination of the cards to the users. A significant drawback lay in the difficulty in installing the prior art cards as part of a publication so that a reader, stimulated by the advertising material, would be able to readily use the card in a foolproof and reliable manner.

These drawbacks have been avoided and resolved by the instant invention through the provision of a unitary paperboard card of generally rectangular configuration having a transverse line of potential folding so as to provide a flap, the flap being equipped with a U-shaped pattern of a remoistenable adhesive so as to provide a pocket or trap for the coin or folded bill to be sent through the mail. Additionally, the card is equipped with an integral extension along one longitudinal edge and separable therefrom along a line of perforation. The integral extension constitutes an advantageous surface for the carrying of advertising information, and in addition provides the means for applying the extension-equipped postcard to a publication or the like at high speed in a reliable fashion. For this purpose the extension along the longitudinal edge portion remote from the integral postcard portion is equipped with a band of adhesive at the time of application, and also a plurality of aligned openings suitable for engagement by a pin feeder mechanism.

DETAILED DESCRIPTION

The invention is described in conjunction with an illustrative embodiment in the accompanying drawing in which:

FIG. 1 is a plan view of the inventive postcard shown installed on a page of a publication, such as the Sunday supplement, and in a condition suitable for use;

FIG. 2 is a plan view of the coin-carrying postcard shown detached from the remainder of the assembly of FIG. 1 and with a coin positioned for receipt within the adhesive-equipped flap;

FIG. 3 is a plan view of the structure of FIG. 2 but with the flap shown in a closed position and enclosing the coin;

FIG. 4 is a bottom plan view of the structure of FIG. 3;

FIG. 5 is an enlarged fragmentary sectional view such as would be seen along the sight line 5—5 of FIG. 1; and

FIG. 6 is a sectional view taken along the line 6—6 of FIG. 3.

In the illustration given, and with reference first to FIG. 1, the numeral 10 designates generally a sheet from a Sunday newspaper supplement or other publication. Adhesively attached to the page 10 is a generally rectangular unitary paperboard blank generally designated 11 and which is seen to consist of two integral but separable parts 12 and 13. The part 12 is separable from the part 13 by virtue of detachment along a line of perforations at 14, and the part 12 thereafter becomes the previously referred-to postcard coin carrier.

A typical coin is seen in FIGS. 2, 3, and 6 and is designated by the numeral 15. For enclosing the coin 15 I equip the postcard part 12 with a score line as at 16 (see FIGS. 1 and 2). The line 16 is a line of potential folding, and after the flap portion 17 is folded about the line 16 the flap portion 17 overlies the coin 15 in the fashion shown in FIGS. 3 and 6.

The flap portion 17 is equipped with a U-shaped pattern 18 of remoistenable adhesive. Thus U-shaped pattern as disclosed has the bight portion of the U immediately adjacent one transverse edge of the card part 12 and with the legs of the U extending longitudinally to the line of potential folding 16. This results in a blank portion 19 which provides a pocket for the coin 15.

Advantageously the paperboard blank 11 has a thickness of at least about 0.006 inches. In the preferred embodiment illustrated, the length of the card portion 12—and therefore, advantageously, the entire blank 11—is at least about 7 inches. Further, the width of the entire blank 11 is advantageously about 6 inches. With the line of perforations 14 being centrally longitudinally of the blank, the result is a division of the blank into equal size mailing parts and advertising parts, 12 and 13 respectively. In the illustration given, the transverse line of potential folding 16 is located closer to the left hand transverse edge than the right hand transverse edge so as to develop a folded postcard having a length of about 5 inches. This results in a 2 inch flap 17 so as to accommodate readily coins such as a quarter or a half-dollar. In certain instances, the length dimension of the folded secured card 20 (see FIGS. 3 and 4) may be shortened somewhat to have outside dimensions of three inches by 4 and $\frac{1}{4}$ inches.

The pattern 18 of adhesive advantageously is made up of arm portions 18a and 18b of equal size and a bight portion 18c. Each of the portions of the U-shaped pattern 18 has about the same width—this being of the order of one-half inch.

As can be seen particularly from FIGS. 2 and 3, the right hand portion of the postcard part 12 is equipped with mailing indicia including the usual address 21 and stamp 22. The reverse side of the flap 17 is provided with a space for the insertion of return mail information as at 23 (see FIG. 3). The remainder of the reverse side is seen in FIG. 4, and this advantageously may be equipped with indicia or information for ordering merchandise and the like, the indicia being designated 24 in FIG. 4.

It will be appreciated that the blank 11 can be advantageously printed on both sides prior to application to the page 10. Inasmuch as the printing is performed while the blank includes the integral extension 13, additional advertising information can be placed on the upwardly facing surface of the blank 13 as is indicated by the numeral 25 in FIG. 1.

Further, during the processing or development of the blank 11, the extension along the edge 26 remote from the postcard part 12 is equipped at the time of application to the page 10 with a band of adhesive 27 (see FIG. 5) which is utilized for adhesively securing blank 11 to the page 10. Alternatively, the extension may be attached by stitching or the like. Still further, the extension 13 adjacent to the edge 26 is equipped with a plurality of circular openings 28 (see FIG. 1) which can be utilized by a sheet feeder mechanism (not shown), but which usually is equipped with pins for the high speed

and accurate advance and positioning of one sheet or blank relative to another.

In the procedure for preparing and installing the blank 11, a web is provided which, in the preferred form, is either 6 inches wide or a multiple of 6 inches, thereby providing parallel blank-containing webs. The web or webs are printed on both sides with a "repeat" or series of successive patterns of 7 inches—this printing including not only the informational indicia, but also the patterns of adhesive as at 18 and 27. Advantageously, the adhesive patterns are of a hot melt which can be dried quickly, but equally quickly remoistened with water for intended usage. Also during the processing, the continuous web containing the 7 inch repeats is equipped along one longitudinal edge with the aligned openings 28. Thereafter, the web containing the 7 inch repeats is zig-zag folded along the repeat barrier and is available for convenient shipping to the point of application to the Sunday supplement. This can be done advantageously through high speed equipment such as the Waldron-Harting "Ad-sert" or Custom-Bilt machinery "Apollo Ad-A-Card" equipment which employs the pin feed holes 18 for high speed feeding.

In use by the reader of the Sunday supplement page 10, the postcard part 12 is conveniently detached from the remainder of the blank 11 by ripping along the line of perforations 14. The order form indicia 24 and return address information 23 can be completed, after which the coin 15 is positioned substantially as seen in FIG. 2. Thereafter, the pattern 18 of the adhesive is moistened and the flap 17 folded along the score line 16 to enclose the coin and provide a structure of the character seen in FIG. 3. The pocket 19 resulting therefrom is formed with a single fold, making it much easier and neater for a customer to use, as well as being more likely to be handled without problem by postal authorities.

While in the foregoing specification a detailed description of an embodiment of the invention has been set down for the purpose of illustration, many varia-

tions in the details herein given may be made for those skilled in the art without departing from the spirit and scope of the invention.

I claim:

- 5 1. A postcard coin carrier comprising a unitary paperboard blank having a thickness of at least 0.006 inches, a longitudinal dimension of at least 7 inches, and a transverse dimension of at least 6 inches, said blank being centrally equipped with a longitudinally extending line of perforations to divide said blank into a mailing part and an advertising part of substantially equal size, a plurality of longitudinally aligned circular openings in said advertising part adjacent the longitudinal edge remote from said mailing part and adapted to receive pins of a sheet feeder mechanism, said mailing portion being equipped with mailing indicia on the right hand portion of one surface thereof and with a transverse line of potential folding positioned adjacent to but spaced from the left hand transverse edge of said blank when said blank is positioned with said one surface upward to divide said mailing part into a larger mailing indicia portion and a flap portion, said flap portion being equipped with a moistenable adhesive on said one surface and arranged in a U-shape, said U-shape providing arms connected at corresponding ends by a bight with said bight being located immediately adjacent said left hand transverse edge and said arms being located immediately adjacent the longitudinal edges of said flap portion with said arms extending approximately to said line of potential folding, said arms and bight being of a width in relation to the size of said flap portion to provide an adhesive free area capable of overlying a coin, said advertising part being equipped with a band of adhesive on the surface opposite said one surface, said adhesive being aligned with and interrupted by said circular openings, said advertising part being adhesively secured through said band of adhesive to a page of a publication whereby the securement to said page is substantially spaced from said line of perforations.
